UNITED STATES PATENT OFFICE.

RICHARD V. KAIMER, OF NEW HAVEN, CONNECTICUT, ASSIGNOR TO THE ENGLISH & MERSICK CO., OF NEW HAVEN, CONNECTICUT, A CORPORATION.

LATCH FOR VEHICLE DOORS.

1,411,107.

Specification of Letters Patent. Patented Mar. 28, 1922.

Application filed August 2, 1921. Serial No. 489,264.

To all whom it may concern:

Be it known that I, RICHARD V. KAIMER, a citizen of the United States, residing at New Haven, in the county of New Haven 5 and State of Connecticut, have invented a new and useful Improvement in Latches for Vehicle Doors; and I do hereby declare the following, when taken in connection with the accompanying drawings and the characters of reference marked thereon, to be a full, clear, and exact description of the same, and which said drawings constitute part of this application, and represent, in—

Fig. 1 a side view of a handle for vehicle 15 door latches constructed in accordance with my invention and shown as applied to the upper end of the latch-spindle.

Fig. 2 a vertical sectional view of the same.

20 Fig. 3 a top or plan view of the same.

Fig. 4 a sectional view on the line 4—4 of Figure 1.

This invention relates to improvement in latches for vehicle doors and is an improvement 25 particularly to latches which are operated in part by a push-button mounted in a vertically-arranged rotatable latch-spindle, and is an improvement in the device shown and described in an application filed May 30 17, 1921, Serial No. 470,366.

In the device shown in the said application, the handle was secured to the spindle by means of a frictional clamp. A more 35 convenient means of securing the handle to the spindle is to flatten two sides of the spindle and provide the hub of the handle with two flat faces to engage therewith, and secure the handle to the spindle by a nut, and the object of this invention is to provide 40 means for attaching a handle to a latch-spindle and provide an operating push-button which will extend up through the handle, and the invention consists in the construction as hereinafter described and particularly recited in the claims.

In carrying out my invention I employ the usual latch-spindle 5, which is a vertical spindle adapted to be rotated for the movement of the lock, as in the application 50 above referred to, and around this spindle is a sleeve 6 adapted to be pressed downward by means of a transverse-pin 7 operated by a push-rod 8. In this construction, the upper end of the spindle is formed on

opposite sides with flattened faces 9 and 10, 55 and that end is threaded to receive a nut 11 which enters a recess 12 in the hub 13 of a handle 14, this nut having a central opening 15 for the passage through it of a button 16 on the end of the push-rod 5. 60

Preferably, and as shown, this nut is polygonal, so that it may be readily applied by suitable wrench and serves not only to hold the push-button in place but to secure the handle to the end of the spindle. 65

With this construction, the handle is firmly secured to the spindle, and the push-button mounted in the spindle for coaction with the sliding sleeve thereon, and the handle brought down closer to the door casing 70 than was possible in the construction shown in the said prior application.

I claim:

1. The combination with a vertically-arranged rotatable latch-spindle having its 75 outer end flattened on opposite sides and with a central bore, a push-rod mounted in said bore and formed with a push-button projecting above the upper end of the spindle, a handle formed to fit the flattened end 80 of the spindle and formed with a chamber into which the spindle extends, and a nut entering the said chamber and engaging with the upper end of the spindle, the said nut formed with a central opening for the 85 passage of the push-button.

2. The combination with a vertically-arranged rotatable latch-spindle having its outer end flattened on opposite sides and with a central bore, a push-rod mounted in 90 said bore and formed with a push-button projecting above the upper end of the spindle, a handle formed to fit the flattened end of the spindle and formed with a chamber into which the spindle extends, and a nut 95 entering the said chamber and engaging with the upper end of the spindle, the said nut formed with a polygonal head and a central bore for the passage of the said push-button. 100

In testimony whereof, I have signed this specification in the presence of two subscribing witnesses.

RICHARD V. KAIMER.

Witnesses:

RUTH E. BRADLEY,
MARY J. MORRISON.
